UNITED STATES PATENT OFFICE.

FRED E. TOOTHAKER, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

DEVICE FOR USE IN TURNING HEEL PORTIONS OF MOLDED-COUNTER TURNED SHOES.

1,405,531.

Specification of Letters Patent. Patented Feb. 7, 1922.

Application filed June 28, 1920. Serial No. 392,223.

To all whom it may concern:

Be it known that I, FRED E. TOOTHAKER, a citizen of the United States, residing at Swampscott, in the county of Essex and 5 State of Massachusetts, have invented certain Improvements in Devices for Use in Turning Heel Portions of Molded-Counter Turned Shoes, of which the following description, in connection with the accompanying 10 drawings, is a specification, like reference characters on the drawings indicating like parts in the several figures.

This invention relates to the manufacture of shoes and is herein illustrated as embodied in a device for use in turning right side out the heel portion of a shoe to which a molded counter is attached.

In the manufacture of turned shoes having molded counters according to the method 20 set forth in the patent to Thissell No. 1,302,994, the counter is attached to the shoe while the shoe is wrong side out upon the first last, the subsequent turning of the shoe right side out serving to bring the upper 25 into contact with the outside of the counter. Hitherto in the turning of the heel portion of the shoe, a so-called bench spindle has been used which comprises a base having in its upper end a small spindle. In turning 30 the heel portion of the shoe, the shoe after removal from the first last, is placed with the attached counter facing downwardly and the upper end of the spindle engaging the extreme rear end of the sole where it is 35 joined to the counter. The operator then grasps the heel portion of the upper on opposite sides of the shoe and pulls or pushes it downwardly, thereby turning it right side out about the counter. Inasmuch as the shoe 40 is supported during this operation only by the end of the comparatively small spindle, which has been referred to above, it is very liable to slip and to move angularly about its point of suspension, such slipping and angular 45 movement interfering with the rapid and satisfactory accomplishment of the turning operation.

According to the present invention a shoe-supporting member is provided which will 50 maintain the shoe firmly in the desired position during the turning of the heel portion.

The illustrative device comprises a shoe-supporting plate having a substantially flat face and an outline which corresponds approximately to the outline of the bottom of the inside of the heel portion of the shoe. Such a plate, by reason of its extended surface offers a firm support against the force of the turning operation and by reason of its shape tends also to hold the shoe from 55 angular movement.

Ordinarily a plate of this kind will be effective to prevent angular movement of the shoe; but, in order to provide for particularly refractory shoes, there is provided a 60 toe holder in the form of a hook or equivalent member which is adapted to extend over the toe portion of the shoe and prevent the toe portion from rising during the turning of the heel portion.

These and other features of the invention, including certain details of construction and combinations of parts, will be described as embodied in a particular machine and pointed out in the appended claims.

Referring now to the accompanying drawings,—

Fig. 1 is an elevation of a device in which the present invention is embodied;

Fig. 2 is a view of the toe-holder looking 80 in the direction of the arrow 2 in Fig. 1;

Fig. 3 is a view showing more particularly the heel plate and its mounting looking in the direction of the arrow 3 in Fig. 1, and

Fig. 4 is a plan of the heel plate.

A base 5, designed to be placed upon a bench, has in its upper portion a split socket to receive a rod 7, the rod being vertically adjustable and held in adjusted position by a pinch-bolt 9. The head of the rod is substantially disk-shaped and provided with a horizontal bore to permit passage therethrough of a bolt 11 which clamps to one side of the head a carrier 13, a nut 14 and spring washer 16 being provided which, together with the bolt 11, hold the carrier frictionally in any angular position to which it may be adjusted. The carrier has driven into it near its forward end a pin 19, and has located near its rear end a threaded bore, 90 the purpose of the pin and bore being, as will presently appear, to provide means for

95

100

locating and fastening in place any one of a series of interchangeable shoe supporting plates. One of these plates 17 is shown in Figs. 1, 3 and 4. It has a substantially flat 5 work supporting face and an outline which corresponds approximately to that of the bottom of the inside of the heel portion of the shoe. In other words, it is adapted to fit snugly into the bottom of the counter with 10 its rear and side edges in substantial contact with the inside wall of the counter. The plate has formed in it a smooth bore 20 adapted to receive the upper end of the pin 19 of the carrier, and a countersunk bore 22 15 adapted to register with the threaded bore in the carrier. A screw 21 passes through the bore 22 in the plate and extends into the threaded bore in the carrier. The plate may 20 thus be readily removed and replaced by one 25 of a different shape or size.

The device as thus far described is entirely adequate for use in turning the heel portion of most molded counter turned shoes. By adjusting the rod 7, the supporting plate may be brought to the desired 30 height, and by tipping the carrier 13 about its pivot bolt 11, the desired angular position may be secured. The pinch-bolt 9 holds the rod firmly in adjusted vertical position; 35 and the nut 14 and spring washer 16 hold the carrier firmly enough in angular position so that this position will not change when force is applied to the heel portion of the shoe to turn it right side out, the relative 40 position of the supporting plate 17 to the pivot 11 being such that there is no strong tendency for the carrier and plate to swing. Attention is directed particularly to the shape of the plate. Its substantially 45 flat work-engaging upper face presents an extended area for contact with the bottom of the inside of the shoe and therefore presents a firm support. Its rear and side edges fit snugly against the curved wall of the 50 molded counter. In this connection it should be borne in mind that the side walls of a molded counter are curved inwardly and therefore tend to hug the plate 17 and to aid in resisting any tendency of the shoe 55 to swing angularly during the turning of the heel portion.

With certain types of shoes it may be desirable to provide further means for preventing such angular movement, and to this 60 end there is provided a toe holder which may be used if desired. This toe holder, as illustrated, comprises a hook 23 which extends over the toe portion of the shoe, the stem of the hook being adjustably held in a split socket in an arm 25 by a pinch-bolt 27. The lower end of the arm extends into a recess in the base 5, its lower end having a bore to receive a pivot rod 29 to which it is fastened by a pin 31. One end of the rod 65 has a bearing in one side of the base (the

left-hand side as viewed in Fig. 2) and the other end extends through a bore in the other side of the base, the latter end being threaded to receive a clamping nut 33 and a check nut 35. Mounted on the rod between the hub of the arm 25 and the right-hand side of the base (as viewed in Fig. 2) is a friction-washer 37; and mounted also on the rod between the outside of the base and an iron washer 39 is a second friction-washer 41. The nuts are set up sufficiently so that the arm 25 will be held frictionally in any position to which it may be adjusted. 70 75

In using the device the operator makes 80 the proper adjustments to bring the plate 17 into the most convenient vertical and angular positions. He then takes a shoe, which is wrong side out and has a molded counter attached right side up to the heel 85 portion of its sole, and places the shoe upon the device with the plate 17 fitting into the bottom of the counter. With the shoe thus supported, he grasps the heel portion of the upper on both sides of the shoe and pushes 90 it down over the counter thereby turning the heel portion right side out. As shown in Fig. 1, this turning operation has been about completed. 95

The description of the use of the device 100 which has been given above presupposes that the toe holder is not used. In case it is desirable to use the toe holder, this member is adjusted into the desired position before the shoe is placed on the device. After its 105 adjustment the shoe is placed as shown in Fig. 1 with the hook 23 extending over the toe portion of the shoe, and then the turning of the heel portion is carried out. It will be understood that the heel portion of a 110 shoe such as has been described is turned first and that the subsequent turning of the toe portion of the shoe may be accomplished in any usual manner.

Although the invention has been described as embodied in a particular device, it should be understood that the present invention is not limited in the scope of its application to the particular device which has been shown and described. 115

Having thus described my invention, what I claim as new and desire to secure by Letters Patent of the United States is:

1. A device for use in turning the heel portion of a shoe to which a molded counter 120 is attached, having in combination, a base and a shoe-supporting member mounted thereon, said member being shaped to enter and fit into the bottom of the counter while the shoe is wrong side out, there being a 125 free and unobstructed space above and at all sides of the member to permit the heel portion of the upper of the shoe to be grasped by the operator and pulled over the counter. 130

2. A device for use in turning the heel portion of a shoe to which a molded counter is attached, having in combination, a base and a shoe-supporting member mounted thereon and angularly adjustable with respect thereto, said member being shaped to enter and fit into the bottom of the counter while the shoe is wrong side out. 5
3. A device for use in turning the heel portion of a shoe to which a molded counter is attached, having in combination, a base, a substantially upright stem carried by the base, and a plate carried at the upper end of the stem, said plate being shaped to fit 10 into the lower portion of the molded counter and being inclined to the axis of the stem.
4. A device for use in turning the heel portion of a shoe to which a molded counter is attached, having in combination, a base, and a plate carried thereby and angularly adjustable with respect thereto, said plate being shaped to fit into the lower portion of the molded counter. 20
5. A device for use in turning the heel portion of a shoe to which a molded counter is attached, having in combination, a base and a shoe supporting member mounted thereon, said member being shaped to fit 25 into the inside of the counter and of a length to terminate in the vicinity of the forward ends of the wings thereof.
6. A device for use in turning the heel portion of a shoe to which a molded counter is attached, having in combination, a base and a shoe supporting member mounted thereon and angularly adjustable with respect thereto, said member being shaped to fit 30 into the inside of the counter and of a length to terminate in the vicinity of the forward ends of the wings thereof.
7. A device for use in turning the heel portion of a shoe to which a molded counter is attached, having in combination, a base, a shoe supporting member angularly adjustable thereon, said member being shaped to fit 35 into the bottom of the counter, and means constructed and arranged to permit said angular adjustment and to hold the member in any position to which it may be adjusted. 50
8. A device for use in turning the heel portion of a shoe to which a molded counter is attached, having in combination, a base, a shoe supporting member angularly adjustable thereon, said member being shaped to fit 40 into the bottom of the counter, and friction means for holding the member in any angular position to which it may be adjusted.
9. A device for use in turning the heel portion of a shoe to which a molded counter is attached, having in combination, a base, a rod vertically adjustable in the base, a carrier angularly adjustable on the rod, and a plate removably attached to the carrier, the 55
- plate being shaped to fit into the bottom of the molded counter. 10
10. A device for use in turning the heel portion of a shoe to which a molded counter is attached, having in combination, a base, a carrier supported thereby and having a substantially flat face, and a plate mounted on the flat face of the carrier and shaped to fit 60 into the bottom of the counter, the plate and carrier having co-operating locating and fastening means such that the plate may readily be removed and replaced. 70
11. A device for use in turning the heel portion of a shoe to which a molded counter is attached, having in combination, a base, an upright rod vertically adjustable with respect thereto, a carrier angularly adjustable with respect to the rod, and a plate mounted on the carrier and shaped to fit 65 into the bottom of the counter. 75
12. A device for use in turning the heel portion of a molded counter turned shoe having, in combination, a base, a rod vertically adjustable in the base, a carrier mounted on the rod and angularly adjustable with respect thereto and a plate mounted on the carrier, said plate being shaped substantially to fit 70 into the bottom of the counter, and means for locating the plate accurately upon the carrier and for fastening it removably in place such that it may readily be removed and replaced. 90
13. A device for use in turning the heel portion of a shoe to which a molded counter is attached, having in combination, means for supporting the heel portion of the shoe, and a member for engaging the toe portion of the shoe to prevent the shoe from being moved angularly during the turning operation. 100
14. A device for use in turning the heel portion of a shoe to which a molded counter is attached, having in combination, means for supporting the heel portion of the shoe, a member for engaging the toe portion of the shoe to prevent the shoe from being moved angularly during the turning operation, and means whereby said member may be adjusted longitudinally. 105
15. A device for use in turning the heel portion of a shoe to which a molded counter is attached, having in combination, means for supporting the heel portion of the shoe, a member for engaging the toe portion of the shoe to prevent the shoe from being moved angularly during the turning operation, and means whereby said member may be adjusted angularly. 110
16. A device for use in turning the heel portion of a shoe to which a molded counter is attached, having in combination, means for supporting the heel portion of the shoe, a member for engaging the toe portion of the shoe to prevent the shoe from being moved angularly during the turning operation. 115
17. A device for use in turning the heel portion of a shoe to which a molded counter is attached, having in combination, means for supporting the heel portion of the shoe, a member for engaging the toe portion of the shoe to prevent the shoe from being moved angularly during the turning operation, and means whereby said member may be adjusted angularly. 120
18. A device for use in turning the heel portion of a shoe to which a molded counter is attached, having in combination, means for supporting the heel portion of the shoe, a member for engaging the toe portion of the shoe to prevent the shoe from being moved angularly during the turning operation, and means whereby said member may be adjusted angularly. 125
19. A device for use in turning the heel portion of a shoe to which a molded counter is attached, having in combination, means for supporting the heel portion of the shoe, a member for engaging the toe portion of the shoe to prevent the shoe from being moved angularly during the turning operation. 130

tion, and means whereby said member may be adjusted both longitudinally and angularly.

17. A device for use in turning the heel portion of a shoe to which a molded counter is attached, having in combination, a member shaped to extend into the bottom of the

counter, and a member adapted to engage the outside of the unturned toe portion of the shoe.

In testimony whereof I have signed my name to this specification.

FRED E. TOOTHAKER.
